UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 14,512, dated December 25, 1883.

Application filed October 27, 1883. Term of patent 3½ years.

To all whom it may concern:

Be it known that I, SARAH JANE SHIELS, of the city, county, and State of New York, have invented and produced a new and original 5 Design for a Pattern of a Lady's Costume, (numbered 8,930;) and I do hereby declare that the engraved prints accompanying this specification convey to any one accustomed to using paper patterns a clear understanding of 10 how a garment made up by the pattern will appear.

The design shows a Princess dress having closely-fitted fronts, with buttons from the throat to some distance below the waist-line, 15 a close-fitting back, a deep front drapery displaying a narrow panel between two wide side

draperies, showing lengthwise-plaits near their front edges, and surmounted by a short tablier that exhibits shirrs at each end and at the left side of the center, and a deep full back drapery that is draped by plaits in the top and deep loops at the sides. Coat-sleeves and a standing collar are added.

What I claim as my invention, and desire to secure by Letters Patent, is—

The design for a lady's costume, as shown in the engraved prints accompanying this specification.

SARAH JANE SHIELS.
